UNITED STATES PATENT OFFICE.

EUGENE A. FORD, OF UXBRIIDGE, MASSACHUSETTS.

SELF-STARTER FOR ENGINES.

1,157,211.

Specification of Letters Patent. Patented Oct. 19, 1915.

Application filed December 18, 1911. Serial No. 666,390.

To all whom it may concern:

Be it known that I, EUGENE A. FORD, of Uxbridge, Worcester county, Massachusetts, have invented new and useful Improvements 5 in Self-Starters for Engines, which invention is fully set forth in the following specification.

My invention is designed especially as a self-starting means for explosive engines in 10 use on automobiles, motor-boats and other self-propelled vehicles, but may obviously be used for starting stationary engines.

Generally, my objects are to provide an efficient and reliable self-starter of compact, 15 durable and relatively simple construction, and one which may be readily controlled by an operator and be inexpensively applied to engines already in use.

A further object of the invention is to 20 provide a self-starter which will act as a fly-wheel and which may readily be mounted on engine shafts in the place now occupied by the usual fly-wheel.

The invention will be better understood 25 by reference to the accompanying drawings, which illustrate one expression of the inventive idea, and wherein,

Figure 1 is a vertical sectional view on line 1—1 of Fig. 3; Fig. 2 is a sectional detail on line 2—2 of Fig. 1; Fig. 3 is a vertical section on line 3—3 of Fig. 1; and Fig. 4 is a horizontal section on line 4—4 of Fig. 1.

8 is the crank-shaft or other suitable shaft 35 of an explosive or internal combustion engine, adapted to be driven by said engine, or when rotated by other power to actuate the pistons of the engine and thereby start the engine. Said shaft may be supported in 40 bearings in any of the usual ways and in the drawings herein is shown as passing through a part 9 of any suitable frame-work. Instead of fly-wheels such as commonly employed, I propose to substitute a fly-wheel 45 comprising in its construction means for starting the engine.

10 is a fly-wheel keyed to shaft 8 and hollow to form a chamber or reservoir 11 for storing motive fluid (preferably air) under 50 pressure pumped into said chamber through supply passages 12, 12, each having a check-valve 13 at its inner end. The passages 12, 12, lead to two pumps, respectively, each pump comprising a cylinder 14 having an 55 outlet-valve 15, a piston having an intake-valve 16 at the inner end of an inlet-passage

18 through the piston, and a pin 19 rotatably engaging a socket in the outer end of the piston. The pins 19, 19, are carried by the pitmen 20, 21, respectively, said pitmen 60 being actuated by eccentrics 22, 23 engaging (with interposed bearing balls) circular openings in the pitmen respectively. The eccentrics are fixed and for this purpose may be secured to part 9 of the frame-work as by 65 pins or rods shown in dotted lines in Fig. 3. The fly-wheel 10 also comprises in its construction a fluid-pressure non-combustion motor. A ring 24 is secured to side wall 25 of the chamber 11, and an annulus or ring 70 26 is secured to said ring 24. As thus made up the fly-wheel presents a recess in its left-hand side, with the pumps located in said recess, and a peripheral groove (about the ring 24) in which there is positioned a ring 75 27, adapted to rotate with the fly-wheel as a part thereof when the shaft 8 is being driven by the engine, but in starting the engine, to remain fixed as the abutment or stationary part of the fluid-pressure motor against 80 which the motive fluid expands in imparting movement to the fly-wheel and shaft. With ring 27 rotating with the fly-wheel as a part thereof in the direction of the arrow, Fig. 1, said ring is temporarily locked to the 85 ring 24 by two latches or plungers 28, 28 positioned equi-distant in transverse recesses 30 on opposite sides of ring 24. Springs 29 tend to force the latches outward into engagement with coacting notches in the inner 90 surface of the ring 27, and an orifice 31 leading from each recess 30 gives atmospheric pressure behind each latch. But with the ring 27 acting as an abutment, and the expansion of the motive fluid tending to rotate 95 it in a direction the reverse of the arrow, Fig. 1, such ring is prevented from so rotating by any suitable means, such as the pawl 32, pivoted to a suitable part of the frame-work, and engaging one of a series of 100 notches 33 in the periphery of the ring.

The periphery of the ring 24 is recessed or cut-away to form between its outer surface and the inner closely fitting surface of the ring 27, two oppositely positioned approximately quarter-circle or arc-shaped expansion-chambers 34, 35, each having an exhaust port 36 leading to the atmosphere, and an inlet-port 37 communicating with a supply conduit 38 leading into the motive-fluid 110 storage reservoir 11. Conduits 38 are normally closed by spring-actuated valves 39,

39, whose valve-rods are connected to a ring 40 keyed on shaft 8 to rotate therewith but free to move longitudinally thereon.

41 and 42 are the arms of the forked end 5 of a shifter-lever having inwardly projecting studs engaging a peripheral groove on ring 40. Said shifter-lever may be under control of an operator, (as the driver of an automobile) by means of a hand or foot lever, 10 whereby the ring 40 may be shifted to the left, Fig. 4, and thereby open the valves 39, 39. In the inner face of said ring 27 there is provided a plurality of recesses 43, and 15 eight equi-distant recesses are herein shown. In each recess there is secured an abutment 44 which is pressed toward ring 24 by a spring 45. Preferably said abutments are pivoted in recesses 46 which communicate with recesses 43.

20 The operation of the device is as follows: A suitable supply of air under a predetermined pressure (maintained by any suitable exhaust valve, not shown) having been stored in reservoir 11 during the running of the 25 engine, and it being desired to again start the same, the operator opens valves 39 by sliding ring or sleeve 40 longitudinally of shaft 8, and accordingly compressed air passes through conduits 38 into expansion 30 chambers 34 and 35. The tendency of the air, acting on abutments 44, is to rotate the ring 27 in a counter clockwise direction, but such a movement is prevented by pawl 32; accordingly, the ring 27 is maintained stationary, and the compressed air, acting on the inclined walls 47 of expansion chambers 34 and 35, rotates ring 24 and the associated parts, in a clockwise direction. The pressure in chambers 34 and 35 is exhausted 35 when ports 36 pass the abutments on which the compressed air is acting. The operator permits the compressed air to pass into chambers 34 and 35 until the engine is started whereupon he releases ring 40 and the 40 valves 39 are closed by springs 48. The compressed air in chambers 34 and 35 having been exhausted, the rapidly rotating ring 24 will "pick up" ring 27, either by frictional engagement or through the medium of latches or plungers 28, and said ring 45 27 will thereupon participate in the rotation of ring 24 and the associated parts, and the whole will then operate to perform the functions of the usual fly-wheel.

50 By referring to Fig. 1, it will be observed that the two recesses 43 in the ring 27, which are shown as being engaged by plungers 28, have cut-away portions 28' associated therewith. The plungers 28 cannot 55 enter any of the other recesses 43, because said recesses do not have these cut-away portions. When, therefore, ring 24 is revolved under the influence of the compressed air, the plungers 28 will pass under the abutments in recesses 43, which have no cut-

away portions, but as soon as the plungers reach, for example, the position shown in Fig. 1, they will enter the cut-away portions 28'. Then, by reason of this engagement, ring 27 will participate in the rotation 70 of ring 24. Rings 24 and 27 are disengaged when compressed air is admitted to chambers 34 and 35, as the air forces the plungers 28 inwardly against their springs 29, thus removing said plungers from the cut-away 75 portions 28' of recesses 43 into which they projected.

80 While the particular expression of the inventive idea herein illustrated has been described in considerable detail, it is to be understood that the invention is not limited to the particular structure shown but that the limits of the invention are indicated in the claims hereto appended.

85 What is claimed is:—

1. In an engine starter, the combination with a shaft adapted to be driven by the engine and connected to the pistons thereof, and means other than the engine for rotating said shaft and thereby starting the engine, said means comprising a rotatable reservoir or chamber for the storage of fluid under pressure, pumping means for pumping fluid into said reservoir carried by the latter and rotating therewith, a fluid-expansion non-combustion motor arranged with its driven part to rotate said shaft, and means under control of an operator for admitting fluid under pressure from the reservoir or chamber to said fluid pressure motor. 90

95 2. The combination with a shaft to be driven by the engine and connected to the pistons thereof, of a fly-wheel embodying in its construction a source of fluid supply and a fluid pressure motor adapted to rotate said shaft to start the engine, and means under control of an operator for supplying motive fluid to said motor from said source of fluid supply. 105

110 3. The combination with a shaft to be driven by the engine and connected to the pistons thereof, of a fly-wheel embodying in its construction a source of fluid supply and means driven by said fluid for actuating said shaft to start the engine. 115

120 4. A fly-wheel embodying in its construction a storage chamber or receptacle for motive fluid under pressure, a moving element, and means for admitting fluid under pressure from said chamber or receptacle to said moving element. 125

130 5. A fly-wheel embodying in its construction a storage chamber or receptacle for motive fluid under pressure, a fluid-pressure non-combustion motor, and means for admitting fluid under pressure from said reservoir to said motor.

6. The combination of a shaft adapted to be driven by an explosive engine and when driven by other power to actuate said engine 135

to start the same, of a wheel on said shaft adapted to serve as a fly-wheel and comprising in its construction a storage chamber or reservoir for fluid under pressure, pumping means actuated upon rotation of the wheel for charging said chamber with fluid under pressure, and a non-combustion fluid-pressure motor, and means under control of an operator for admitting fluid from said chamber or reservoir to said motor to thereby actuate the motor.

7. In combination, a shaft, a wheel mounted thereon, a reservoir carried by said wheel, means automatically supplying fluid under pressure to said reservoir, a fluid-pressure non-combustion motor, and means under control of the operator for admitting fluid to said motor from said reservoir.

8. In combination, a shaft, a wheel mounted thereon, a reservoir carried by said wheel, means operated by said shaft automatically supplying fluid under pressure to said reservoir, a fluid-pressure non-combustion motor, and means under control of the operator for admitting fluid to said motor from said reservoir.

9. In combination, a shaft, a fluid-pressure non-combustion motor mounted thereon and comprising in its construction a member keyed to said shaft and rotatable therewith, a second member forming with the other member a pressure chamber, means admitting fluid under pressure to said chamber, an exhaust port associated with said chamber and an abutment which is stationary when fluid under pressure is admitted to said chamber and which rotates with said member when the pressure in said chamber is exhausted.

10. In combination, a shaft, a wheel on said shaft comprising in its construction a reservoir and a member keyed to said shaft and rotatable therewith, a second member forming with the other member a pressure chamber, means admitting fluid under pressure from said reservoir to said chamber, an exhaust port associated with said chamber, and an abutment which is stationary when fluid under pressure is admitted to said chamber and which rotates with said reservoir and member when the pressure in said chamber is exhausted.

11. In combination, a shaft, a wheel on said shaft comprising in its construction a reservoir and a member keyed to said shaft and rotatable therewith, a second member forming with the other member a pressure chamber, means under the control of the operator admitting fluid under pressure from said reservoir to said chamber, an exhaust port associated with said chamber, and an abutment which is stationary when fluid under pressure is admitted to said chamber and which rotates with said reservoir and

member when the pressure in said chamber is exhausted.

12. In combination, a shaft, a fluid-pressure non-combustion motor mounted thereon and comprising in its construction a member keyed to said shaft and rotatable therewith and provided with a cut-away portion, a rotatable ring maintained stationary until said shaft is rotated and associated with said member and provided with abutments which engage said cut-away portion, means admitting fluid under pressure to said cut-away portion and an exhaust port associated with said cut-away portion.

13. In combination, a shaft, a fluid-pressure non-combustion motor mounted thereon and comprising in its construction a member keyed to said shaft and rotatable therewith and provided with a cut-away portion, a ring associated with said member and provided with abutments which engage said cut-away portion, means admitting fluid under pressure to said cut-away portion and an exhaust port associated with said cut-away portion, said ring being stationary when fluid under pressure is admitted to said cut-away portion and rotatable with said member when the pressure in said cut-away portion is exhausted.

14. In combination, a shaft, a wheel on said shaft comprising in its construction a reservoir and a member keyed to said shaft and rotatable therewith, a ring associated with said member, an abutment carried thereby, said ring, member and abutment inclosing a pressure chamber, means admitting fluid under pressure to said chamber and an exhaust port associated with said chamber, said ring being stationary when fluid under pressure is admitted to said chamber and rotating with said member when the pressure in said chamber is exhausted.

15. In combination, a shaft, a wheel on said shaft comprising in its construction a reservoir and a member keyed to said shaft and rotatable therewith, means automatically supplying fluid under pressure to said reservoir, a ring associated with said member, an abutment carried thereby, said ring, member and abutment inclosing a pressure chamber, means admitting fluid under pressure to said chamber, and an exhaust port associated with said chamber, said ring being stationary when fluid under pressure is admitted to said chamber and rotating with said member when the pressure in said chamber is exhausted.

16. In combination, a shaft, a wheel on said shaft comprising in its construction a reservoir and a member keyed to said shaft and rotatable therewith, means operated by said shaft and automatically supplying fluid under pressure to said reservoir, a ring associated with said member, an abutment car-

ried thereby, said ring, member and abutment inclosing a pressure chamber, means admitting fluid under pressure to said chamber and an exhaust port associated with said chamber, said ring being stationary when fluid under pressure is admitted to said chamber and rotating with said member when the pressure in said chamber is exhausted.

16 17. In combination, a shaft, a wheel on said shaft comprising in its construction a reservoir and a member keyed to said shaft and rotatable therewith, a ring associated

with said member, an abutment carried thereby, said ring, member and abutment 15 inclosing a pressure chamber, means admitting fluid under pressure to said chamber, and an exhaust port associated with said chamber.

In testimony whereof I have signed this 20 specification in the presence of two subscribing witnesses.

EUGENE A. FORD.
